SHIELD FOR A PRECISION BALANCE

Kenneth Le Roy Beller, 1613 W. Flora St.,
Santa Ana, Calif. 92704

Filed Oct. 9, 1967, Ser. No. 8,931

Term of patent 14 years

The portion of the term of the patent subsequent to
Jan. 10, 1981, has been disclaimed

Int. Cl. D10—08

U.S. Cl. D52—10

FIG. 1 is a perspective view of a shield for a shield for a precision balance showing my new design;

FIG. 2 is a side elevational view thereof; and

FIG. 3 is a rear elevational view thereof.

The broken line representation of a precision balance in FIG. 1 is for purposes of illustration only.

I claim:

The ornamental design for a shield for a precision balance, substantially as shown and described.
